CLAIM

The ornamental design for a panel with pattern, as shown and described.

DESCRIPTION

FIG. 1 is a front perspective view of a panel as used in a partition structure;

FIG. 2 is a front perspective view thereof;

FIG. 3 is a front elevational view thereof;

FIG. 4 is a cross-sectional view taken in the direction of line 4-4 in FIG. 3;

FIG. 5 is a cross-sectional view taken in the direction of line 5-5 in FIG. 3;

FIG. 6 is a cross-sectional view taken in the direction of line 6-6 in FIG. 3; and,

FIG. 7 is a cross-sectional view taken in the direction of line 7-7 in FIG. 3.

The broken lines shown in the drawings illustrate environmental subject matter that forms no part of the claimed design. The broken lines adjacent to the claimed design represent a boundary that forms no part of the claimed design.
